ASSIGNORS TO NILES-BEMENT-POND COMPANY, OF JERSEY CITY, NEW JER-
SEY, A CORPORATION OF NEW JERSEY.

PLANER.

1,321,203.

Specification of Letters Patent. Patented Nov. 11, 1919.

Application filed October 19, 1916, Serial No. 126,522. Renewed November 15, 1917. Serial No. 202,240.

To all whom it may concern:

Be it known that we, GEORGE E. GREENLEAF and HAROLD L. BLOOD, citizens of the United States, and residents of Plainfield, in the county of Union and State of New Jersey, have invented certain new and useful Improvements in Planers, of which the following is a specification.

It will be understood that when we refer to a planer we intend to include any mechanism, particularly a machine tool, which comprises an element (such as a work carrying table) adapted to travel forward and backward, and an element (such as a cutting tool) coöperating with the table and provided with means whereby relative transverse feeding can be effected between the said element and the said table; and it will be further understood that with certain obvious modifications the invention can be applied to a planer or other machine in which the tool instead of the work support is reciprocated.

The invention relates particularly to planers having a power actuated tool feeding device which is automatically controlled, preferably electrically, by means of the reciprocating planer table, and which preferably comprises a motor, such as an electric motor, independent of the main planer driving means; and the invention is especially adapted for a planer having a reversible electric motor directly connected to the reciprocating table to drive it, but, as concerns certain features, it is not limited to a planer having such a drive motor.

One object of the invention is to provide a planer having a power feeding device and means for causing the said device to operate under one set of conditions during the preliminary adjusting of the tool or tools and under another set of conditions during normal feeding, each set of conditions being particularly advantageous for the work being done. When the feeding device is a separate electric motor the connections are such that the current has one circuit during adjusting and another circuit during feeding. An electric motor when used is preferably so connected that during feeding it rotates always in the same direction.

Another object of the invention is to provide a planer having a power feeding

device or motor and also having a master controlling device or switch supplemental to and independent of the device or switch which normally controls the feeding device or motor during ordinary operation, this master controlling device or switch preferably being manually operable and adapted to operate the feeding device or motor to effect preliminary adjustments of the tool or tools.

A further object of the invention is to provide, in combination with a reversible electric drive motor and an electric tool feeding motor, an arrangement of mechanical elements or electrical connections or both, which permits the control in an improved way of either the drive motor or the feed device, or both, by means of the same controlling mechanism.

Other objects of the invention will be apparent from the following specification and the claims.

The invention can be embodied in any one of a number of ways, particularly as concerns the mechanical features thereof; but in order that one embodiment of the invention may be clearly understood, we have shown in the drawings and will herein describe a planer, the mechanical construction of which is similar to that set forth in the Greenleaf and Keefer Patent No. 1,299,192 dated April 1st, 1919. For details of the construction in addition to those herein set forth, reference can be had to the said patent. Some of the electrical features of the invention are also similar to those set forth in the said Greenleaf & Keefer patent. However, it will be understood that as concerns both the mechanical and the electrical features, the drawings and the description are to be understood as merely illustrative and are not to be construed as defining or limiting the scope of the invention, the claims appended to this specification being relied upon for that purpose.

Of the drawings:

Figure 1 is a side elevation of a planer embodying the invention.

Fig. 2 is a front elevation.

Fig. 3 is a diagram of electrical connections.

Referring particularly to Figs. 1 and 2

of the drawings, 1 represents the planer bed, 2 the reciprocating table, 3 and 4 the uprights or housings and 5 the arch connecting the uprights. Driving mechanism is provided for reciprocating the table 2 on its bed, and so far as certain features of the invention are concerned this driving mechanism can be of any usual or preferred form. We prefer, however, to use an electric motor which is directly geared to the table and which is reversible to effect the reciprocation thereof, such a motor having especial advantages in connection with a planer embodying the more characteristic features of our invention as will fully appear. A reversible electric motor is indicated in the drawings at 6, the gearing connections between it and the table being of any usual or preferred form. When such a motor is used there is provided a controller 7. For operating certain parts of the controller and for other purposes there is provided a pilot switch 8. This switch is operated by means of a rod 9 connected to levers 10 and 10^a which are engaged respectively by dogs 11 and 12 secured to the reciprocating table. These dogs are adjustable to regulate the length of the stroke.

Cooperating with the reciprocating table to act upon work carried thereby, there are one or more cutting tools. So far as the broader phases of our invention are concerned, the number of tools and the relative positions of the tools are immaterial. We prefer, however, to provide four tools as shown in the drawings. In the construction illustrated there is a vertically movable cross rail 13 which is fitted to vertical guides on the uprights 3 and 4. Transversely movable along the cross rail 13 are one or more (in this case two) tool heads 14 and 15. Preferably also there are provided two side tool heads 16 and 17 which are vertically adjustable along the guides on the uprights 3 and 4.

For moving one or more of the tool heads either to effect preliminary adjustment of the tools or to effect feeding thereof during operation of the planer, we provide a power device which by preference is electrically controlled and which also by preference is a motor generating power independently of the main planer drive. An independent electric motor constitutes the simplest and most advantageous power device for the purpose of our invention, and such a motor has been shown for the purpose of illustrating the invention. In the drawings the motor is indicated at 18, it preferably being mounted upon the arch 5.

For connecting the motor with the tool heads we prefer to use mechanism which, as aforesaid, is similar to that set forth in the Greenleaf & Keefer application Serial No. 228,809. It will be necessary herein to

refer only to the essential features of this mechanism as reference can be had to the said application for the several details.

In Fig. 1 one of the tools is indicated at 19, this being carried by a clapper and clapper box 20 secured to a slide 21 vertically movable on the saddle of the tool head 14. For the sake of clearness the tools and the clappers and clapper boxes have been omitted from the Fig. 2. For moving the slides 21 vertically with respect to their saddles, adjusting screws 22 are provided which can be operated manually if desired by means of a crank such as shown at 23. Splined upon each of these screws is a bevel gear 23^a 80 which is connected with a bevel gear 24 loosely mounted on a transverse shaft 25 rotatable in bearings on the cross rail 13. By means of clutch elements splined to the shaft 25 and controllable respectively by the hand levers 26 and 27, either of the gears 24 can be connected with the shaft 25 so that when the shaft 25 is rotated the corresponding screw 22 will be turned to raise or lower the corresponding slide 21 and the tool carried thereby.

Transverse threaded screws 28 and 29 are provided to respectively control the transverse movements of the tool heads 14 and 15, these screws being parallel to the shaft 25 and similarly mounted.

The shafts and screws 25, 28 and 29 can be moved manually when desired, as for instance, by means of a crank 30 as indicated in Fig. 2. In order that the shafts may be rotated by power, a spur gear 31 is mounted at one end of the cross rail in position to mesh with pinions 32, 33 and 34 detachably mounted respectively on the ends of the shafts 29, 25 and 28. Each of these pinions is preferably in the form of a "click box" having a reversible ratchet device which, for each position of adjustment, permits transmission of power from the pinions to the shafts in one direction only. The construction is therefore such that by putting in place or removing the click boxes and by properly adjusting the ratchet devices thereof one or more of the shafts or screws can be intermittently moved in one direction 110 or the other, as desired, when the gear 31 is oscillated; or one or more of the shafts or screws can be continuously moved in one direction or the other, as desired, when the gear 31 is continuously moved. For actuating the gear 31 there is provided a crank arm 35 at one side of the gear and a gear 36 at the other side thereof, both of these devices being loosely mounted. By means of a suitable clutch mechanism, either the 115

crank 35 or the gear 36 can be connected with the gear 31. A gear 37 meshes with the gear 36 and a feed plate 38 is connected with the crank 35 by means of a connecting rod 39 and an adjustable pin 39^a the said 120

gear and feed plate being connected together and driven by means of a bevel gear 40. Two vertical shafts 41 and 42 are mounted on the uprights 3 and 4 and are 5 driven by the motor 18 through worm and wheel gearing at 43 and 44. Splined on the shaft 41 is a bevel gear 45 which meshes with the aforesaid bevel gear 40 and thus transmits power to rotate the gear 36 by 10 means of the gear 37 and to oscillate the crank 35 by means of the feed plate 38 and the connected rod 39. It will be seen that if the motor be operated to rotate the feed plate 38 through a definite angle, as for instance 15 through a whole revolution or a half revolution, and that if the gear 31 be connected with the crank 35, one or more of the shafts 25, 28 and 29 will be rotated in one direction or the other as required 20 through a definite angle, thus moving one or the other or both of the tool heads to the right or to the left as required or moving one or the other or both of the slides 21 upward or downward as required. If the 25 motor 18 be operated continuously in one direction or the other and if the gear 31 be connected with the gear 36, then either or both of the tool heads can be moved continuously in either direction as required or 30 either or both of the slides 21 can be moved continuously in either direction as required.

For the purpose of adjusting the cross rail 13 vertically, two screws 46 and 47 are provided which are connected by means of 35 suitable bevel gearing with a transverse shaft 48 connectible with the motor 18 by means of gearing 49 and a clutch 50 manually operable by means of a lever 51. It will be seen that by engaging the clutch 50 and starting the motor 18 in one direction or the other the cross rail 13 may be raised or lowered as required.

The side tool heads 16 and 17 can be provided with cross slides and other means 45 of tool adjustment as required, such parts being shown in Fig. 1 but omitted in Fig. 2 for the sake of clearness. For controlling the vertical movement of the side heads vertical screws 52 and 53 are provided. 50 Splined upon each of these screws is a nut rotated by a bevel gear 54 which meshes with a bevel gear 55 on a transverse shaft 56 carried by the corresponding tool head. By rotating this shaft 56 either manually 55 or by power, the tool head may be raised or lowered. For applying power to the shaft 56 of each tool head there is provided a bevel gear 57 which is splined to the corresponding vertical shaft 41 or 42. Each 60 gear 57 meshes with a gear 58 and the gear 58 drives a mechanism 59 which is similar to that already described for applying power to the shafts 25, 28 and 29. A repetition of the description is unnecessary, and 65 it will be understood that when the motor

is rotated through a definite angle either or both of the tool heads 16 and 17 can be raised or lowered as required through a definite distance, and that when the motor is rotated continuously either or both of 70 the tool heads can be moved continuously upward or downward as required. It will be observed that the amount of movement of either side head can be adjusted independently of the amount of movement of 75 the cross heads.

For controlling the flow of current to the feed motor 18, there is provided a motor operated limit switch, it preferably though not necessarily being operated by the feed 80 motor itself. This limit switch is indicated at 60 in Fig. 1, it being mounted on one of the shafts 41 or 42, as for instance 41. The operation of the limit switch will be explained in connection with the description of the electrical connections. A master 85 switch for effecting the control of one of the motors (or either of them if desired) is shown at 61. This master switch is preferably connected at the end of a flexible 90 cable which is so supported as to hold the switch at a point within convenient reach of the operator. Because of this preferred form of mounting the master switch is commonly known as a pendent master switch. 95 The full purpose of the master switch and the electrical connections therefor will be explained hereinafter.

Referring now more especially to the electrical connections as shown in Fig. 3, it will 100 be noted that the feed motor is indicated by the reference character 18 as in the other figures. The feed motor 18 is provided with a shunt field winding 62 and connected in series with the armature of the motor is 105 a suitable resistance. Preferably this resistance is divided into two parts, one of the parts being indicated at 63 and the other of the parts being in the form of a series field winding as indicated at 64. It will 110 be understood, however, that so far as concerns certain phases of the invention one or the other of these parts may be omitted.

For controlling the operation of the feed motor a starting switch is provided as indicated at 65, this switch preferably forming a part of the switch 8 heretofore mentioned as a pilot switch operated by the reciprocating table. It will be understood however, that when reference is made to a table 115 operated switch we mean to include any switch which is operated in synchronism with the table reciprocations, and we do not mean to limit ourselves to a switch directly connected in the way shown. Preferably, 120 the starting switch 65 controls the motor indirectly by means of an electromagnetic relay switch 66. This relay switch 66 and the actuating magnet 67 therefor can conveniently be mounted as a part of the con- 125 130

troller shown at 7 in Fig. 1. In conjunction with the feed motor there is provided a transfer switch 68 preferably of the three pole double throw type. For normal operation of the feed motor to effect intermittent feeding the transfer switch 68 is in its upper position as shown in Fig. 1.

The circuit for the coil of the relay magnet 67 extends from the positive lead 69^b 10 to the coil and from the coil it extends through the connection 70 to a stationary contact 71^a of the starting switch 65. The switch is provided with another stationary contact 72 which is connected by means of a 15 wire 73 with the negative lead 74^b. A movable contact 75 on the switch 65 is adapted to connect the contacts 71^a and 72, thus completing the circuit through the magnet 67 and causing the core thereof to be lifted 20 to close the switch 66. When the switch 66 is closed a circuit is completed through the feed motor as follows: from the positive lead 69^b through the central pole of 25 the switch 68, the switch 66, the motor armature, the resistance 63, the right-hand pole of the switch 68, the series field 64 and back to the negative lead 74^b. It will be understood that the shunt field 62 is continuously energized through the wire 76. 30 The motor therefore starts operation and by means of the mechanical connections that have been described, serves to move one or more of the tool heads in the desired manner. By providing shunt and series fields 35 of the required strengths and by varying the amount of the resistance 63 in the circuit the torque and speed of the motor can be regulated as desired. The resistance 63 serves to reduce the danger of injuring the 40 motor in case one of the tools becomes jammed or for any reason fails to move freely.

The operation of the motor will continue until the relay magnet is deenergized to 45 permit the switch 66 to open. The magnet can be deenergized by opening its circuit at the starting switch 65, but preferably there is provided a limit switch which acts automatically to open the circuit after the motor 50 has rotated to a predetermined extent or after the tool or tools have been moved to a predetermined extent. Mention has already been made of the limit switch 60 which is mounted on the shaft 41 and is therefore 55 movable to an extent proportionate to the extent of movement of the motor. The switch 60 is provided with three stationary contacts 77, 78 and 79 and with three connected movable contacts 80, 81 and 82. The 60 contact 81 is a ring continuously engaging the contact 78, and the contacts 80 and 82 are interrupted rings adapted respectively to engage the contacts 77 and 79 alternately as the shaft is rotated. To complete the circuit 65 from the switch 60 to the switch 65 the con-

nection 70 is constructed in two parallel sections 70^a and 70^b, the section 70^a connecting the contacts 77 and 71^a and the section 70^b connecting the contacts 79 and 71^b, which latter contact is similar to the aforesaid contact 71^a. With the switch 60 in the position shown in Fig. 3 the circuit extends from the wire 70 through the contacts 78, 81, 80 and 77, the wire 70^a and the contacts 71^a, 75 and 72 to the wire 73. As the motor rotates the switch 60 is moved to disengage the contact 80 from the contact 77, thus breaking the relay circuit and causing the switch 66 to open. At or about the same time the contact 82 engages the contact 79 thus partly reestablishing the relay circuit in preparation for the next movement of the motor. After the switch 66 has been opened and after the motor has stopped it remains idle until the starting switch 65 is moved to again complete the relay circuit, the circuit this time extending through the wire 70^b instead of the wire 70^a as before. When the circuit is thus completed the motor starts as before and continues operation until the contact 82 is disengaged from the contact 79. In this way the motor is started at intervals as the table reciprocates, the relay circuit being established alternately through the wires 70^a and 70^b, and after each starting 90 the limit switch 60 serves to stop the motor after rotation to a predetermined extent. 95

We prefer to have the feed motor rotate always in the same direction during normal feeding operation, but so far as certain features of our invention are concerned, such operation is not essential. There are, however, certain advantages incident to such operation, one of the more important of which is the possibility of providing a series 100 field winding without complicated switch connections such as would be necessary if the motor were to be rotated alternately in opposite directions. A series field such as we have provided is desirable as it keeps down 110 the starting current and provides a large starting torque.

Preferably, in order that the motor and the tool heads may not continue movement by momentum after the switch 66 is opened, 115 we provide for short circuiting the motor armature to effect dynamic braking. At the lower end of the core of the magnet 67 there is provided a switch 83 which is open when the motor is in normal operation but which 120 is automatically closed when the switch 66 is opened. When the switch 83 is closed a short circuit extends from the motor armature through the core of the magnet 67, the switch 83, the resistance 63 and back to the 125 armature. It is to be observed that this short circuit includes only one part of the resistance which is normally in circuit with the armature. The part of the resistance which is in the form of the series field 130

is automatically excluded while dynamic braking is taking place. If this series field were left in it would oppose the shunt field and lessen the braking action.

5 As already stated, it is desirable to operate the feed device or motor continuously in order to effect traversing, that is, movement of the cross rail vertically or movement of one or more of the tool heads in the 10 desired directions to effect preliminary adjustments. Normally, as stated, the feed motor is under the control of the starting switch 65 and the limit switch 60, which latter switch serves to interrupt the motor movement. To effect traversing the limit switch 15 60 is prevented from acting, thus making it possible for the motor to be operated continuously. When the feed motor is so operated it is preferable to give it a higher 20 speed than it has during normal feeding. The increase in speed can be obtained in any one of the several ways, but we prefer to secure the desired increase in speed by cutting out resistance from the armature circuit, this resistance by preference being the 25 series field. Preferably there is provided a master device supplemental to the starting switch 65 for controlling the motor during traversing, such a master device being desirable because it is inconvenient (although 30 not impossible) to operate the starting switch 65 manually. The master device is preferably a pendent switch such as that already briefly mentioned and shown in Fig. 35 1 at 61.

The transfer switch 68 when moved from its upper to its lower position enables the motor to be operated for traversing in the manner referred to. Such a movement of 40 the transfer switch 68 serves to cut out the limit switch 60. Preferably, when the master switch such as 61 is provided, the movement of the transfer switch 68 also serves to cut out the starting switch 65, thus making possible the control of the motor by the master switch 61. A circuit is established from the wire 70 through the right-hand pole of the switch, the series field 64 and back to the negative lead 74^b. In this 45 way the magnet 67 is continuously energized and the relay switch 66 is kept closed. At the same time the series field receives no current (except the energizing current for the magnet 67 which is negligible), and 50 55 it is therefore rendered substantially ineffective.

For the reasons already stated, it is desirable for the motor to operate always in the same direction during normal feeding 60 operation, but when the motor is to be used for traversing it is desirable that it be reversible. Therefore the master device, in this case the switch 61, is preferably so constructed and connected that the motor 65 can not only be started and stopped but can

also be reversed. The master switch 61 preferably, though not necessarily, acts indirectly to control the motor, there being provided a relay motor controlling mechanism. This controlling mechanism is adapted to cause the motor to operate in either direction. 70

So far as our invention is concerned, the controlling mechanism may be of any one of a number of sorts, but we prefer and have shown a mechanism in many respects similar to that set forth in Patent 1,003,269 to Keefer. This mechanism comprises two operating magnets 84 and 85 adapted respectively when their cores are lifted to close 80 switches 86 and 87 and open switches 88 and 89. Associated with said switches there are preferably blow-out magnets 90 and 91, the magnet 91 preferably also co-operating with the switches 66 and 83. The transfer switch 85 86, when in its lower position for traversing, connects the feed motor with this mechanism, and it will be seen that when the switch 86 is closed and the switch 88 opened, a circuit for the motor is completed as follows: from the positive lead 69^b through the coil of the blow-out magnet 90, the switch 89, the core of the magnet 85, the left-hand pole of the switch 68, the armature, the switch 66, the central pole of the switch 68, 95 a part of the resistance 92, and the switch 86 back to the negative lead 74^b. The motor is thus connected for rotation in one direction. 90

Rotation of the motor continues until the 100 switch 86 is opened and the switch 88 closed. Then the motor circuit is broken and a short circuit to effect dynamic braking is established as follows: from the armature through the left-hand pole of the switch 68, the core 105 of the magnet 85, the switch 89, the left-hand blow-out magnet 90, the right-hand blow-out magnet 91, the switch 88, the core of the magnet 84, a part of the resistance 92, the central pole of the switch 68, the switch 66, 110 and back to the armature.

When the switch 87 is closed and the switch 89 opened a circuit through the motor is established in a manner similar to that already described except that the current flows through the armature in the opposite direction and the rotation is reversed. When the switch 87 is again opened and the switch 89 again closed, a short circuit to 115 effect dynamic braking is established in the 120 way already described.

The speed of rotation can be controlled by varying the amount of a resistance 92 in the circuit, but preferably the speed will be greater than that during feeding for the 125 reason that the series field is rendered substantially ineffective as already stated. This in addition to increasing the speed, makes it possible for the motor to be easily reversed without complicated switch connections 130

and the series field is not needed to assist in starting as the motor is started only occasionally instead of repeatedly at short intervals as during normal feeding operation.

For energizing the magnets 84 and 85, relay circuits are provided which are controllable by means of the master switch 61. The circuit for the magnet 84 extends from 10 the positive lead 69^b through wires 93 and 94, preferably through a normally closed switch 95 at the lower end of the blow-out magnet 91, and through the magnet coil to a contact 96 of the switch 61. The circuit for the magnet 85 extends through the wire 93, preferably through a normally closed switch 97 at the lower end of the blow-out magnet 90, and through the magnet coil to a contact 98 of the switch 61. The switch 20 61 is also provided with contacts 99 and 100 each of which is connected with the negative lead 74^b by means of a wire 101. The switch 61 has a movable contact 102 which can be moved upward from the position 25 shown in Fig. 3 and turned to the right or the left to connect either the contacts 96 and 99 or the contacts 98 and 100. If 96 and 99 are connected the magnet 84 is energized and the motor rotated in one direction, and 30 if 98 and 100 are connected the magnet 85 is energized and the motor rotated in the other direction. When the contact 102 is moved to central position, neither of the 35 magnets is energized and the motor is short circuited for dynamic braking. The aforesaid switches 95 and 97 are connected to be opened by the blow-out magnets 91 and 90 when those magnets are energized. It will therefore be seen that so long as the short 40 circuit current is flowing the magnets will be energized and will hold open the switches 95 and 97, thus preventing the energization of either of the magnets 84 or 85 to reverse the motor.

45 As was stated at the outset, we prefer a reversible electric motor for driving the planer table. When such a driving motor is used it is possible, and in fact preferable, to control it by means of the same controlling 50 mechanism which has been described as adapted for controlling the feed motor to effect traversing. In Fig. 3 the driving motor is indicated by the reference character 6 as in the other figures. The motor is provided with a shunt field winding 103 and 55 preferably with an interpole winding 104 and an extra series winding 105.

The transfer switch 68 is so connected 60 that a circuit of the drive motor extends therethrough when the switch is in its upper feeding position, the said circuit being broken when the switch is moved to its lower traversing position. When the switch 68 is in its upper position the drive motor 65 can be started in one direction by closing

the switch 86 and opening the switch 88, the following circuit being established: from the positive lead 69^b through the coil of the magnet 90; the switch 89, the core of the magnet 85, the left-hand pole of the switch 68, the motor armature, the interpole winding 104, a part of the resistance 92, and the switch 86, back to the negative lead 74^b. In order to speed up the motor for starting, there is preferably provided a supplemental controlling magnet 106 adapted to close a switch 107 and open a switch 108. Both contacts of the switch 108 are insulated from the core of the magnet 106. The operating circuit for this magnet is connected across 70 the armature terminals of the motor in such a way that as the counter electromotive force of the motor increases the magnet is energized to close the switch 107 and open the switch 108. The closing of the switch 107 serves to short circuit the interpole winding 104 and the starting resistance 92, the circuit extending directly from the armature through the switch 107 to the switch 86. At starting the shunt field 103 75 is energized through a circuit including the wire 93, the switch 108 and a wire 109. The opening of the switch 108 breaks this circuit and places in series with the field more or less of a cutting resistance 110, the circuit 80 extending through a switch 111 which is normally closed. Thus by cutting out the interpole winding and the starting resistance and by weakening the field the motor 85 is brought to the correct speed for driving the table in the cutting direction, this speed being adjustable by varying the amount of the cutting resistance in circuit with the shunt field.

When the magnet 84 is deenergized to 105 open the switch 86 and close the switch 88 a dynamic short circuit through the motor armature is established, this circuit being similar to that already described in connection with the operation of the feed motor. 110 The short circuit current of the motor 6 being more powerful than that of the motor 18, energizes the magnets 90 and 91 sufficiently to open the switches 97 and 95, thus preventing the energization of the magnets 115 84 and 85 so long as any considerable short circuit current flows. When the short circuit current drops to a predetermined value the switches 95 and 97 are permitted to close, thus making it possible for one or the other 120 of the magnets 84 and 85 to be energized. When the magnet 85 is energized to close the switch 87 and open the switch 89 the operation is similar to that already described except that the motor is connected for rotation in the opposite direction. The magnet 85 also serves to open the switch 111 so that when the switch 108 is opened the shunt field circuit is established not only through the cutting resistance 110 but also through 125 130

a return resistance 112. In this way a weaker field is provided and the motor is given a much higher speed for the return stroke, this speed being adjustable by varying the amount of the return resistance in the circuit. When the magnet 85 is de-energized a dynamic short circuit through the motor armature is established in the way already described.

10 The controlling mechanism, including the magnets 84 and 85 can be operated in the manner already described by the master switch 61, and such operation is frequently desirable during preliminary adjustments 15 of the tools and of the work on the table. However, during normal operation of the planer it is necessary to provide for the automatic operation of the controlling mechanism to reverse the motor at intervals as 20 the table reciprocates. A table operated device or switch is provided and for the operation of the controlling mechanism, this preferably being the before mentioned pilot switch 8.

25 In the construction illustrated the said table operated pilot switch 8 is provided with stationary contacts 96^a and 98^a corresponding respectively with the contacts 96 and 98 of the master switch 61. Other contacts 99^a and 100^a are provided, these being connected together and corresponding respectively with the contacts 99 and 100 of the master switch 61. The pilot switch 8 has movable contacts 114 and 114^a adapted 35 respectively to connect the contacts 96^a and 99^a and the contacts 98^a and 100^a. When the pilot switch is in one position one pair of contacts is connected to energize one magnet and when the pilot switch is moved at 40 the end of the table reciprocation the first pair of contacts is disconnected and the other pair connected to stop the motor and reverse it to drive the table in the opposite direction. There are also two contacts 115 45 and 116 which are in the circuit of the magnet 106. These contacts are connected by one or the other of the contacts 114 and 114^a so that the said magnet is energized whenever the motor is in normal operation. During 50 braking, however, the said magnet is de-energized, thus including the interpole winding 104 and the resistance 92 in the dynamic short circuit of the motor.

It will be understood that in cases in 55 which the master switch 61 is omitted the feed motor can be controlled and operated continuously in either direction for traversing by manually operating the pilot switch 8. For such operation of the feed motor the transfer switch 68 will be in its lower position, thus rendering the starting switch 65 and the limit switch 60 inoperative and cutting out the main motor.

60 Preferably the master switch 61 is constructed and connected with the pilot switch

in a manner similar to that set forth in the Keefer reissued Patents 14,539 and 14,540. When the motor is in normal operation the movable element of the master switch 61 is in its lower position as shown in Fig. 3. 70 The switch has contacts 117 and 118 which are connected, these contacts being in the circuit which connects the pilot switch contacts 99^a and 100^a with the negative lead 74^b. When the movable element of the master switch 61 is moved upward to effect the control of the magnets 84 and 85 the contacts 117 and 118 are disconnected, thus rendering the pilot switch inoperative to control the said magnets. This prevents any 80 accidental engagement of the dogs 11 and 12 with the levers 10 and 10^a from interfering with the control of the said magnets by means of the master switch. The master switch 61 is preferably also provided 85 with contacts 119 and 120 which are also connected when the movable element is in its lower position. These contacts are in the circuit of the magnet 106 and when the movable element of the switch is moved upward to control the magnets 84 and 85 the magnet 106 is rendered inoperative, thus making it impossible for the motor to speed up. Thus the master switch 61 can be used 90 to operate the drive motor in either direction only at a slow speed. It will also be noted that the magnet 106 is inoperative to control the feed motor, and that therefore when the feed motor is under the control 95 of the controlling mechanism and the master switch 61 the said motor is operated at 100 the same speed in both directions.

As already stated, the transfer switch 68 serves to interrupt the circuit of the motor 6 when it is moved to its lower traversing 105 position. Thus the same switch which transfers the feed motor from the control of the starting switch 65 and the limit switch 60 to the control of the master switch 61 and the controlling mechanism also serves 110 to render the drive motor inoperative during traversing.

Under some circumstances it is desirable 115 to provide means whereby the beginning of the operation of the feed motor depends upon the speed of the main motor; that is, to provide means whereby the feed motor is started when the speed of the main motor has dropped to a predetermined point. We prefer to make the construction such 120 that the feed motor will start only when the main motor and the table have nearly ceased moving. As already stated, the controlling circuit for the feed motor includes contacts which are connected when the main pilot switch 8 is thrown over, and, in accordance with the present feature of our invention, the controlling circuit for the feed motor also includes an electromagnetic switch which is held open till the speed of 130

the main motor drops to a predetermined point, thus preventing the starting of the feed motor. For this purpose use can conveniently be made of the switches 95 and 97 of the controlling mechanism. These switches are held open so long as any considerable short circuit current flows in the drive motor circuit, this current stopping simultaneously with the stopping of the motor and the table. The coil of the magnet 67 has been described as connected with the positive lead 69^b, and preferably the connection is through the switches 95 and 97 as shown. In this way the energization of the relay switch 66 for starting the feed motor is prevented until near the end of the table movement.

In Fig. 3 we have diagrammatically shown a circuit breaker 121 provided with 20 overload and low voltage releasing coils, this circuit breaker being connected between the positive and negative leads 69^b and 74^b and the main supply leads 69^a and 74^a. This circuit breaker constitutes no part of 25 our present invention and a very brief description will be sufficient. As shown, the circuit breaker includes an overload release coil 122 and a no voltage coil 123. In the case of no voltage the circuit is broken at 30 124. In the case of high voltage the circuit is broken at 125 and the circuit of the no voltage coil is also broken at 126. The circuit breaker is provided with a switch 127 and in the case of either no voltage or high 35 voltage this switch is automatically moved to its closed position, as illustrated. This switch is open during the normal operation of the apparatus. When the switch is closed a short circuit is established through the 40 armature of the motor 6 by means of the wires 128 and 129, this circuit including all of the resistance 92. At the same time, by means of the wire 129 and a supplemental wire 130, the shunt field 103 of the 45 motor is short-circuited upon itself. This short-circuiting of the motor armature and of the shunt field serves to bring the motor quickly to rest in the case of high voltage or no voltage.

50. What we claim is:

1. In a planer or other machine having a reciprocating table and an adjustable tool, the combination with the table and the tool, of a power device for feeding the tool, a 55 starting device automatically operable by the table to effect the intermittent feeding of the tool by the power device as the table reciprocates or manually operable to effect the continuous movement of the tool by the power device for traversing, and means whereby the speed of movement of the tool is increased when the power device is continuously operated for traversing.

2. In a planer or other machine having a 65 reciprocating table and an adjustable tool,

the combination with the table and the tool, of an electric motor for feeding the tool, a table operated starting switch for automatically operating the motor intermittently as the table reciprocates to effect feeding, 70 means for operating the motor continuously to effect traversing, and means whereby the motor is caused to have greater torque when it is intermittently operated to effect feeding than when it is continuously operated 75 to effect traversing.

3. In a planer or other machine having a reciprocating table and an adjustable tool, the combination with the table and the tool, of an electric motor for feeding 80 the tool, a table operated starting switch for starting the motor at intervals as the table reciprocates, a motor controlling mechanism supplemental to the table operated switch, and a transfer switch for placing 85 the motor under the control of the table operated switch or for placing it under the control of the controlling mechanism and simultaneously increasing the motor speed.

4. In a planer or other machine having a 90 reciprocating table and an adjustable tool, the combination with the table and the tool, of an electric motor for feeding the tool, resistance normally in series with the motor armature, means for automatically starting 95 the motor at intervals as the table reciprocates to effect feeding or for operating it continuously to effect traversing, and means whereby the said resistance is rendered substantially ineffective when the motor is 100 operated continuously to effect traversing.

5. In a planer or other machine having a reciprocating table and an adjustable tool, the combination with the table and the tool, of a compound electric motor for feeding 105 the tool, means for automatically operating the motor intermittently as the table reciprocates to effect feeding or for operating it continuously to effect traversing, and means for rendering the series field substantially ineffective when the motor is 110 operated continuously to effect traversing.

6. In a planer or other machine having a reciprocating table and an adjustable tool, the combination with the table and the tool, of an electric motor for feeding the tool, resistance normally in series with the motor armature, a table operated switch for automatically starting the motor at intervals 115 as the table reciprocates, a table operated mechanism supplemental to the said controlling switch, and means whereby the said resistance is rendered substantially ineffective when the motor is under the control of the controlling mechanism.

7. In a planer or other machine having a reciprocating table and an adjustable tool, the combination with the table and the tool, of a compound electric motor for feeding 120 the tool, a table operated switch for starting 125

- the motor at intervals as the table reciprocates, and means for short circuiting the motor armature independently of the series field to effect dynamic braking.
8. In a planer or other machine having a reciprocating table and an adjustable tool, the combination with the table and the tool, of a tool feeding motor, a table operated switch serving to start the motor always in the same direction at intervals as the table reciprocates, a controlling mechanism adapted to connect the motor for movement in either direction, and a transfer switch for placing the motor under the control either of the said starting switch or the said controlling mechanism and for increasing the speed of the motor when it is under the control of the said controlling mechanism. 70
9. In a planer or other machine having a reciprocating table and an adjustable tool, the combination with the table and the tool, of a power device for feeding the tool, a table operated starting device for effecting the feeding of the tool by the power device at intervals as the table reciprocates, and a master device supplemental to and operable independently of the table operated device and adapted for controlling the said power device to effect movements of the tool independently of the table movements. 85
10. In a planer or other machine having a reciprocating table and an adjustable tool, the combination with the table and the tool, of a power device for feeding the tool, a table operated starting device for effecting the feeding of the tool by the power device at intervals as the table reciprocates, a master device supplemental to the table operated device and adapted for controlling the movement of the tool by the said power device, and means for rendering the table operated device ineffective when the master device is in use. 90
11. In a planer or other machine having a reciprocating table and an adjustable tool, the combination with the table and the tool, of an electric tool feeding motor, a table operated switch for starting the motor at intervals as the table reciprocates, and a supplemental controlling master switch operable independently of the table operated switch and adapted for starting stopping and reversing the motor. 105
12. In a planer or other machine having a reciprocating table and an adjustable tool, the combination with the table and the tool, of an electric tool feeding motor, a table operated switch for starting the motor at intervals as the table reciprocates, a master switch supplemental to the table operated switch and adapted for starting stopping and reversing the motor, and means for rendering the table operated switch ineffective when the master switch is in use. 120
13. In a planer or other machine having a reciprocating table and an adjustable tool, the combination with the table and the tool, of an electric tool feeding motor, a table operated switch for starting the motor at intervals as the table reciprocates, a motor controlling mechanism supplemental to the table operated switch, a master switch sup- 130
- reciprocating table and an adjustable tool, the combination with the table and the tool, of an electric tool feeding motor, a table operated switch for starting the motor at intervals as the table reciprocates, a supplemental master switch operable independently of the table operated switch and adapted for starting stopping and reversing the motor, and a transfer switch for rendering the table operated switch ineffective and for causing the master switch to be effective to control the motor. 75
14. In a planer or other machine having a reciprocating table and an adjustable tool, the combination with the table and the tool, of an electric tool feeding motor, a table operated switch for starting the motor at intervals as the table reciprocates, a limit switch operated by the motor and normally serving to stop the said motor after rotation to a predetermined extent, a supplemental master switch operable independently of the table operated switch and adapted for starting stopping and reversing the motor, and means adapted to render the said limit switch ineffective whereby the motor is entirely under the control of the master switch. 80
15. In a planer or other machine having a reciprocating table and an adjustable tool, the combination with the table and the tool, of an electric tool feeding motor, a table operated switch for starting the motor at intervals as the table reciprocates, a limit switch operated by the motor and normally serving to stop the said motor after rotation to a predetermined extent, a master switch supplemental to the table operated switch and adapted for starting stopping and reversing the motor, and a transfer switch for rendering the table operated switch ineffective and for causing the master switch to be effective to control the motor and for rendering the limit switch ineffective whereby the motor is entirely under the control of the master switch. 95
16. In a planer or other machine having a reciprocating table and an adjustable tool, the combination with the table and the tool, of an electric tool feeding motor, a table operated switch for starting the motor at intervals as the table reciprocates, a motor controlling mechanism supplemental to the table operated switch, and a master switch supplemental to the table operated switch and adapted for operating the controlling mechanism to cause the motor to rotate in either direction. 115
17. In a planer or other machine having a reciprocating table and an adjustable tool, the combination with the table and the tool, of an electric tool feeding motor, a table operated switch for starting the motor at intervals as the table reciprocates, a motor controlling mechanism supplemental to the table operated switch, a master switch sup- 125

plemental to the table operated switch and adapted for operating the controlling mechanism to cause the motor to rotate in either direction, and means for rendering the table operated switch ineffective when the master switch is in use.

18. In a planer or other machine having a reciprocating table and an adjustable tool, the combination with the table and the tool, of an electric tool feeding motor, a table operated switch for starting the motor at intervals as the table reciprocates, a motor controlling mechanism supplemental to the table operated switch, a master switch supplemental to the table operated switch and adapted for operating the controlling mechanism to cause the motor to rotate in either direction, and a switch for rendering the table operated switch ineffective and for causing the master switch to be effective to control the motor.

19. In a planer or other machine having a reciprocating table and an adjustable tool, the combination with the table and the tool, of an electric tool feeding motor, a table operated switch for starting the motor at intervals as the table reciprocates, a limit switch operated by the motor and normally serving to stop the said motor after rotation to a predetermined extent, a motor controlling mechanism supplemental to the table operated switch, a master switch supplemental to the table operated switch and adapted for operating the controlling mechanism to cause the motor to rotate in either direction, and means adapted to render the motor operated switch ineffective whereby the motor is entirely under the control of the master switch.

40 20. In a planer or other machine having a reciprocating table and an adjustable tool, the combination with the table and the tool, of a reversible electric table driving motor, an electrically controlled tool feeding device, table operated switch means for reversing the drive motor and for starting the feeding of the tool at intervals as the table reciprocates, and a master switch supplemental to the table operated means for controlling the drive motor or for controlling the feeding of the tool in either direction by means of the said feeding device.

21. In a planer or other machine having a reciprocating table and an adjustable tool, the combination with the table and the tool, of a reversible electric table driving motor, an electrically controlled tool feeding device, table operated switch means for reversing the drive motor and for starting the feeding of the tool at intervals as the table reciprocates, a master switch supplemental to the said table operated means for controlling the drive motor or for controlling the movement of the tool in either direction by means

of the said feeding device, and a transfer switch for placing either the drive motor or the feeding device each independently of the other under the control of the master switch.

22. In a planer or other machine having a reciprocating table and an adjustable tool, the combination with the table and the tool, of a reversible electric table driving motor, an electric tool feeding motor, table operated switch means for reversing the drive motor and for starting the feed motor at intervals as the table reciprocates, and a master switch supplemental to the table operated means for controlling the drive motor or for causing the feed motor to rotate in either direction.

23. In a planer or other machine having a reciprocating table and an adjustable tool, the combination with the table and the tool, of a reversible electric table driving motor, an electric tool feeding motor, a unitary table operated switch adapted to reverse the drive motor and to start the feed motor at intervals as the table reciprocates, and a master switch supplemental to the table operated switch for controlling the drive motor or for causing the feed motor to rotate in either direction.

24. In a planer or other machine having a reciprocating table and an adjustable tool, the combination with the table and the tool, of a reversible electric table driving motor, an electric tool feeding motor, table operated switch means for reversing the drive motor and for starting the feed motor at intervals as the table reciprocates, a master switch supplemental to the table operated means for starting stopping and reversing the feed motor, and means for rendering the drive motor inoperative when the feed motor is under the control of the supplemental switch.

25. In a planer or other machine having a reciprocating table and an adjustable tool, the combination with the table and the tool, of a reversible electric table driving motor, an electric tool feeding motor, table operated switch means for reversing the drive motor and for starting the feed motor at intervals as the table reciprocates, a master switch supplemental to the table operated means for controlling the drive motor or for controlling the feed motor, and a transfer switch for placing either motor each independently of the other under the control of the master switch.

26. In a planer or other machine having a reciprocating table and an adjustable tool, the combination with the table and the tool, of a reversible electric table driving motor, an electric tool feeding motor, a table operated switch means for reversing the drive motor and for starting the feed motor at

intervals as the table reciprocates, means operated by the feed motor and normally serving to stop the said motor after rotation to a predetermined extent, a master switch supplemental to the table operated switch for controlling the drive motor or for starting and stopping the feed motor, and a switch for rendering the motor operated switch ineffective when the feed motor is under the control of the master switch.

27. In a planer or other machine having a reciprocating table and an adjustable tool, the combination with the table and the tool, of a reversible table driving motor, an electric tool feeding motor, table operated switch means for reversing the drive motor and for starting the feed motor at intervals as the table reciprocates, a limit switch operated by the feed motor and normally serving to stop the said motor after rotation to a predetermined extent, a master switch supplemental to the table operated means for controlling the drive motor or for starting and stopping the feed motor, and a transfer switch for placing either motor each independently of the other under the control of the master switch and for rendering the limit switch ineffective when the feed motor is under the control of the master switch.

28. In a planer or other machine having a reciprocating table and an adjustable tool, the combination with the table and the tool, of a reversible electric table driving motor, an electric tool feeding motor, table operated switch means for reversing the drive motor and for starting the feed motor always in the same direction at intervals as the table reciprocates, a master switch supplemental to the table operated means for starting stopping and reversing the feed motor, and a transfer switch for rendering the drive motor inoperative when the feed motor is under the control of the master switch.

29. In a planer or other machine having a reciprocating table and an adjustable tool, the combination with the table and the tool, of a reversible electric table driving motor, an electric tool feeding motor, table operated switch means for reversing the drive motor and for starting the feed motor at intervals as the table reciprocates, a master switch supplemental to the table operated means for controlling the feed motor, and means for rendering the table operated means ineffective to control the drive motor when the feed motor is under the control of the master switch.

30. In a planer or other machine having a reciprocating table and an adjustable tool, the combination with the table and the tool, of a reversible electric table driving motor, an electric tool feeding motor, table operated switch means for reversing the drive motor and for starting the feed motor at intervals

as the table reciprocates, a master switch supplemental to the table operated means either for controlling the drive motor or for controlling the feed motor, and means for rendering the table operated means ineffective to control the drive motor when the master switch is in use to control either motor.

31. In a planer or other machine having a reciprocating table and an adjustable tool, the combination with the table and the tool, of a reversible electric table driving motor, an electric tool feeding motor, a motor controlling mechanism, table operated switch means for operating the controlling mechanism to reverse the drive motor at intervals as the table reciprocates and for starting the feed motor at intervals as the table reciprocates, a transfer switch for placing the feed motor under the control of the controlling mechanism and for disconnecting the drive motor therefrom, and a master switch supplemental to the table operated means and adapted for operating the controlling mechanism.

32. In a planer or other machine having a reciprocating table and an adjustable tool, the combination with the table and the tool, of a reversible electric table driving motor, an electric tool feeding motor, a motor controlling mechanism, table operated switch means for operating the controlling mechanism to reverse the drive motor at intervals as the table reciprocates and for starting the feed motor independently of the controlling mechanism and always in the same direction at intervals as the table reciprocates, a transfer switch for placing the feed motor under the control of the controlling mechanism and for disconnecting the drive motor therefrom, and a master switch supplemental to the table operated means and adapted for operating the controlling mechanism to start stop and reverse either motor.

33. In a planer or other machine having a reciprocating table and an adjustable tool, the combination with the table and the tool, of a reversible electric table driving motor, an electric tool feeding motor, a motor controlling mechanism, table operated switch means for operating the controlling mechanism to reverse the drive motor at intervals as the table reciprocates and for starting the feed motor at intervals as the table reciprocates, a transfer switch for placing the feed motor under the control of the controlling mechanism and for disconnecting the drive motor therefrom, a master switch supplemental to the table operated means and adapted for operating the controlling mechanism, and means for preventing the operation of the controlling mechanism by the table operated means when the master switch is in use.
